DUPLICATING MACHINE

Filed Sept. 4, 1929

UNITED STATES PATENT OFFICE

FRANK CHESLEY, OF LOUISVILLE, KENTUCKY, ASSIGNOR OF ONE-HALF TO ABRAHAM
M. COOPER

DUPLICATING MACHINE

Application filed September 4, 1929. Serial No. 390,351.

This invention relates to duplicating machines, and is particularly directed to a machine in which a minimum sized conveniently applied printing blanket or flexible sheet may be used, and to the features of the machine relative to convenient and rapid application and tensioning of the printing blanket over a platen.

The present commercial type duplicating machines utilize a roll or continuous printing blanket or hectograph sheet which is reset or adjusted over the surface of the platen for a new printing operation after the required number of copies or transfers have been made from an impression or print placed on the special surface of the printing blanket. This form of blanket or hectograph sheet now in use is composed of a layer of gelatin treated with glycerine placed on a backing 20 of cloth, the layer holding the printing, writing, sketching, etc., on its surface for a period of time suitable for printing a number of copies. The printing or writing, after the passage of considerable time, becomes ineffective for contact transfer, since it is absorbed or penetrates into the layer. When the proper time has elapsed, the particular portion of the sheet is again usable.

The machine now commonly in use embodies the printing sheet roll for the purpose of changing the portion of the roll over the platen when it is desired to closely succeed printing operations on the same machine. This roller blanket is of considerable length 35 and therefore quite expensive. Frequently, it is damaged or unequally worn and must be discarded entirely.

In the present invention, printing sheets of short length are used, just sufficient to cover the platen, which sheets are quickly attached and stretched over the surface of the platen by devices at the respective ends of the table holding the platen. After a printing operation, each sheet is removed 45 without difficulty and a fresh printing sheet applied.

It is, therefore, an object of this invention to provide a duplicating machine of simple form, to which individual printing or hectograph sheets for each operation may be

quickly applied and removed. Provision is thus made for a cheaply manufactured machine economically maintained and conveniently operated.

It is another object of this invention to 55 provide a duplicating machine incorporating efficient attaching means or tensioning devices for stretching a printing sheet over the platen, which means are rapidly and easily manipulated and the sheet accurately snapped into position. These mounting devices on the machine are intended for mounting any type of sheet and for mounting either rotatable or stationary spindles.

It is another object of this invention to 60 provide guiding facilities on the machine aiding the operator in uniformly placing the successive sheets, to be printed, on the printing sheet for transfer therefrom.

Other objects relate to the general construction of a simple, portable duplicating machine, which objects and advantages will be more fully set forth in the description of the accompanying drawings, in which:

Figure 1 is a general perspective view of the 75 duplicating machine showing a printing sheet or blanket in position.

Figure 2 is a transverse sectional view illustrating the table construction and the relation of the guide to the printing sheet and platen.

Figure 3 is a sectional view taken on line 3—3, Figure 2, illustrating the sheet attaching or tensioning device at one end of the machine, this view showing the printing sheet disposed in position of use in the device.

Figure 4 is a sectional view taken similar to Figure 3, but illustrating the spindle at the end of the printing blanket or sheet, in position just prior to snapping into place in the attaching device.

The invention as illustrated, described in general, comprises a table 5 having a platen 6 on its surface, tensioning devices 7—7, one mounted on each end of the table, and a guide 8 extending longitudinally on the top surface of the table along the side of the platen. A printing blanket 9 is disposed over the surface of the platen and secured at its respec- 100

tive ends in the attaching devices for proper tensioning of the sheet over the platen.

Referring specifically to the details of the drawings, the table 5 provides a leg 10 at each corner thereof, a rubber button or cushion 11 being secured to the underside of each leg for preventing contact of the metal of the table with the surface upon which the device is placed. The table presents a smooth 10 top upon which a layer of felt, constituting the platen 6, is secured. Each tensioning device comprises a bar 13 having upwardly extending hooks 14 formed integrally therewith at each end, these hooks being outwardly disposed relative to the table.

The bar 13 is mounted transversely across the end of the table, well down below the surface thereof, by means of studs 15, one secured in each end of the bar, these studs extending through the end wall of the table and having threaded ends upon each of which a nut 16 and washer 17 are secured. A tapered coil compression spring 18, surrounding each stud, is disposed between the bar and the wall of the table. The bores 19 through which the studs extend are of greater diameter than the studs, permitting rocking or canting of the studs relative thereto. This rocking takes place between the nuts and 25 the washers and is a vertical movement permitting the hooks to be pressed inwardly against spring pressure.

The printing blanket 9 is a standardized product embodying a layer of gelatin treated 30 with glycerine disposed on a fabric backing. A hem 20 is provided at each end of the blanket being formed by stitching a strip of fabric to the margin of the blanket, the strip overlapped upon the respective sides of the 35 blanket and providing a clearance between the edge of the blanket and the fold of the strip, through which clearance or hem a rod 21 is inserted, this rod or spindle extending from each end of the hem as at 22.

40 The hooks of the tensioning devices are sufficiently spaced apart to permit the width of the blanket and length of hem to be disposed therebetween and the spindles or rods to engage the hooks. The blanket is placed 45 in position by hooking the spindles at one end thereof in the respective hooks, drawing the blanket tautly across the surface of the platen and forcing the tensioning device at the opposite end of the machine inwardly, 50 tipping the hooks with the thumb of each hand, while the forefinger of each hand engages the spindles and forces them over the hook edges, as shown in Figure 4.

The spindles are spaced apart a suitable 55 distance for causing a slight tipping of the tensioning devices when the blanket is in position, this placing the blanket under spring tension at all times, whereby it is tautly engaged over the surface of the platen, the position of the hooks below the surface of the

table aiding in the proper disposition of the blanket on the platen.

The guide 8 is of angle iron form and extends approximately the length of the platen, being secured to the surface of the table along the edge of the platen with the angle inwardly facing. One end of the angle iron guide strip is provided with a transverse flange 23, providing a stop at that end of the guide, and the other end of the angle has 70 the upstanding flange bent downwardly as at 24 to provide a channel for accurate insertion of the sheets to be printed and for preventing rising of the sheet margin relative to the guide.

In operation, a sheet or printing blanket is placed in position as above described. The drawing or printing to be copied is drawn upon an original, using the proper ink or writing instrumentality, which will be readily transferable to the surface of the blanket, placing the original sheet inscribed face down upon the blanket, rubbing or rolling over the sheet, which causes adherence to the blanket. The original is then stripped from the 90 blanket and the writing or drawing has been transferred to the glycerine surface. Thereupon, sheets are successively placed against the surface of the printing sheet against the guide edge and against its stop end until the 95 required number of copies have been made.

Inasmuch as it will require a considerable number of hours for the data on the printing blanket to penetrate the layer of compound, the blanket may be removed and replaced by 100 a fresh blanket. Successive blankets may be used and in the end the first used blankets will be reconditioned by the absorption of the printing into the layer.

Having described my invention, I claim:

1. In a duplicating machine, a table, a tensioning device at each end of the table, said tensioning devices having outwardly facing hooks disposed below the surface of the table, springs for urging said hooks outwardly, 110 and a printing blanket disposed upon the surface of the table, said blanket having spindles attached across its ends engageable with the respective hooks when the hooks are forced inwardly against said springs, whereby the blanket is placed under tension across the surface of the table.

2. In a duplicating machine, a table, a tensioning device at each end of the table, said tensioning devices having outwardly facing 120 hooks, springs for urging said hooks outwardly, and a printing blanket disposed upon the surface of the table and having its ends engageable within the respective hooks when the hooks are forced inwardly against the 125 pressure of said springs, whereby the blanket is placed under tension across the surface of the table.

3. A duplicating machine, comprising, a table, a platen on said table, a tensioning de-

vice at each end of the table, each tensioning device, comprising, a bar providing outwardly disposed hooks at the respective corners of the table, studs extending from said bar through the table, compression springs between the bar and the wall of the table, means for mounting the studs relative to the table, the studs traversing bores of greater diameter than the studs for permitting tilting of the studs relative to the bores, a printing blanket having hems at the ends thereof, and rods traversing said hems and having their ends extending beyond the respective ends of the hems, said extending ends engageable in said hooks upon tilting of the hooks and compression of the springs.

4. A duplicating machine, comprising, a table, a tensioning device at each end of the table, each tensioning device, comprising, outwardly disposed hooks at the respective corners of the table, studs extending from said hooks through the table, compression springs between the hooks and the wall of the table, means for securing the studs relative to the table, the studs traversing bores of greater diameter than the diameter of the studs for permitting tilting of the studs relative to the bores, a printing blanket, and rods secured at the ends of the blanket and having their ends extending beyond the respective said edges of the blanket, said extending ends engageable in said hooks upon tilting of the hooks and compression of the springs.

5. A duplicating machine, comprising, a table, a platen on said table, hooks at the respective corners of the table, studs extending from said hooks through the table, coil compression springs between the hooks and the wall of the table, and means for securing the studs relative to the table, the studs traversing bores of greater diameter than the studs for permitting tilting of the studs relative to the bores, and a printing blanket having rods extending from its corners, said rods engageable in said hooks upon tilting of the hooks and compression of the springs.

In witness whereof, I hereunto subscribe my name.

FRANK CHESLEY.
